UNITED STATES PATENT OFFICE.

FRANK P. DOOLEY, OF CHICAGO, ILLINOIS.

WIRE BED-BOTTOM FABRIC.

1,105,262.

Specification of Letters Patent. Patented July 28, 1914.

Application filed April 13, 1914. Serial No. 831,511.

To all whom it may concern:

Be it known that I, FRANK P. DOOLEY, a citizen of the United States, residing at Chicago, in the county of Cook and State of Illinois, have invented a certain new and useful Improvement in Wire Bed-Bottom Fabrics, of which the following is a full, clear, concise, and exact description, reference being had to the accompanying drawings, forming a part of this specification.

My invention relates to metal fabrics that are of service for example in the construction of furniture and finds a useful embodiment in mattresses or mattress supports. Such fabrics are made of assembled units formed of wire.

My invention relates particularly to fabrics that include component units in their construction that are in the form of major loops, each major loop having a minor loop joining its sides and inturned toward the opposite ends of the major loop. A fabric including loops of this formation is disclosed in my United States Letters Patent No. 1,081,438, patented December 16, 1913, though the invention is not to be limited, in all of its embodiments, to the form of fabric disclosed in said patent.

In such fabric units as those here mentioned the sides of the minor loop and the sides of the major loop between which the minor loop intervenes are in serial order, a major loop side being followed by an adjacent minor loop side which in turn is followed by the remaining minor loop side that is finally followed by the remaining major loop side, none of the wire of the unit being crossed at the minor loop end thereof. A fabric having such units is very efficient when embodied in a structure as set forth in my aforesaid patent but in order to adapt fabric having such units in its formation to the support of very heavy or bouncing loads I have twisted the minor loops about axes substantially lying in the plane of the fabric or the loops thereof in order to cross the sides of the minor loops to prevent these sides from materially spreading apart when subjected to the heavier duty. In the preferred embodiment of the invention the minor loops are interlocked.

I will explain my invention more fully by reference to the accompanying drawing showing the preferred embodiment thereof and in which—

Figure 1 is a plan view of a portion of a broken away fabric; Fig. 2 is a side view of the structure of Fig. 1; Fig. 3 is a perspective view of the preferred form of fabric composing unit; Fig. 4 is a perspective view of a modified fabric composing unit; Fig. 5 is a view of the minor loop end of the fabric unit illustrated in Fig. 3; Fig. 6 is a view on line 6—6 of Fig. 3; and Fig. 7 is a view on line 7—7 of Fig. 3.

Like parts are indicated by similar characters of reference throughout the different figures.

Each wire fabric composing unit is in the form of a major loop whose sides 1, which are preferably straight, terminate each in a hook 2, the sides of each loop being joined at their ends opposite the hooks by a minor loop 3 which is inturned toward the hooks so as to lie between the loop sides 1 of the same loop and substantially in the same plane therewith, whereby each major loop having the sides 1 is provided with two bights 4 instead of one bight and whereby each major loop possesses sufficient resilience to enable it to become a component part of a springy fabric without the necessity of introducing curvature between the bights 4 and hooks 2, though I do not wish to be limited to the absence of this curvature. The

rows of adjacent units desirably extend transversely of the length of the fabric, the units at the ends of these rows being suitably attached as for example to side strips 5. The bights 4 in the units comprising each row receive the hooks 2 of the units comprising an adjacent row, whereon the various rows of units are assembled to constitute the complete fabric which may be attached at its ends to rows of coil springs 6 each anchored at one end to a suitable fabric supporting frame 7 and joined at its other end with the fabric through the intermediation of a suitable link 8. At one end of the fabric the links 8 are connected with the hooks 2. At the opposite end of the fabric the last row of units is joined with the links 8 through the intermediation of links 9.

Each fabric unit illustrated is generally of V-shape, the sides 1 (that are preferably straight) converging from their hook ends 2 toward the minor loops 3. These minor loops of the fabric units in each row are thus immediately disposed between the hook ends 2 of adjacent units in an adjacent row

whereby the employment of links, which themselves afford no cushioning action, is not required for assembling fabric units into a fabric. The loop sides 1 of each unit in each row thus combine with the adjacent loop sides of adjacent units in an adjacent row that are connected with the first-mentioned loop sides at hooks 2 to form figures which are substantially of diamond shape, whereby series of connected portions 1 are disposed in directions that slope with respect to the sides of the fabric, there being substantially no load supporting elements such as unit connecting links or parallel loop sides which extend at right angles to any side of the fabric so that the main load supporting ridges 1 of the fabric perform their load supporting function without being prominently and uncomfortably presented to the load, a result which is enhanced as aforesaid, by the absence of unyielding unit binding links.

The characteristics of the fabric thus very specifically described in connection with the accompanying drawing have been set forth in my aforesaid patent, and while my invention is preferably embodied in a fabric having these characteristics it is not to be limited to such an embodiment.

In practising my present invention the inturned loops 3 are bodily twisted in planes transverse to the general plane of the fabric and the major loops of the fabric units or about axes that lie substantially in the plane of the fabric and the units thereof whereby the sides of the minor loops are crossed once as indicated in Figs. 1, 2, 3, 5, 6 and 7 or more than once as indicated in Fig. 4. The formation illustrated in Figs. 1, 3, 5, 6 and 7 is preferred, the crossed sides of each minor loop forming an eye that will sufficiently oppose undue separation of the sides of the major loop, a result which is desirably promoted by having each minor loop side received in a depression 10 in the complementary minor loop side (Figs. 5, 6 and 7), the sides of each minor loop being thus interlocked though preferably permitting very limited movement where the minor loop sides cross slightly to promote the flexibility of the fabric. In the construction of Fig. 3 the minor loop is twisted through an arc of 180° whereas in the construction of Fig. 4 the minor loop is twisted through a complete circle, the slight relative movability that remains between the minor loop sides in the structure of Fig. 3 being eliminated in the structure of Fig. 4.

While I have herein shown and particularly described the preferred embodiment of my invention I do not wish to be limited to the precise details of construction shown as changes may readily be made without departing from the spirit of my invention, but

Having thus described my invention I

claim as new and desire to secure by Letters Patent the following:—

1. A wire fabric including a plurality of adjacent rows of adjacent units, each unit being in the form of a V-shaped loop having straight sides, which sides terminate, where farthest apart, in hooks, and which sides are joined at their ends opposite the hooks by a minor loop having crossed sides and inturned toward the hooks and affording two separated bights between its sides and the aforesaid sides of the larger loop, these bights formed in each fabric unit of each row being engaged by the hooks in which the adjacent sides of adjacent fabric units in an adjacent row terminate, the sides of each fabric unit in each row forming with the adjacent sides of adjacent fabric units in an adjacent row connected therewith by the hooks of the first fabric unit figures of substantially diamond shape.

2. A wire fabric including a plurality of adjacent rows of adjacent units, each unit being in the form of a V-shaped loop having sides, which sides terminate, where farthest apart, in hooks, and which sides are joined at their ends opposite the hooks by a minor loop having crossed sides and inturned toward the hooks and affording two separated bights between its sides and the aforesaid sides of the larger loop, these bights formed in each fabric unit of each row being engaged by the hooks in which the adjacent sides of adjacent fabric units in an adjacent row terminate, the sides of each fabric unit in each row forming with the adjacent sides of adjacent fabric units in an adjacent row connected therewith by the hooks of the first fabric unit figures of substantially diamond shape.

3. A wire fabric including a plurality of adjacent rows of adjacent units, each unit being in the form of a V-shaped loop having straight sides, which sides terminate where farthest apart, in hooks, and which sides are joined at their ends opposite the hooks by a minor loop having crossed interlocked sides and inturned toward the hooks and affording two separated bights between its sides and the aforesaid sides of the larger loop, these bights formed in each fabric unit of each row being engaged by the hooks in which the adjacent sides of adjacent fabric units in an adjacent row terminate, the sides of each fabric unit in each row forming with the adjacent sides of adjacent fabric units in an adjacent row connected therewith by the hooks of the first fabric unit figures of substantially diamond shape.

4. A wire fabric including a plurality of adjacent rows of adjacent units, each unit being in the form of a V-shaped loop having sides, which sides terminate, where farthest apart, in hooks, and which sides are

joined at their ends opposite the hooks by a minor loop having crossed interlocked sides and inturned toward the hooks and affording two separated bights between its 5 sides and the aforesaid sides of the larger loop, these bights formed in each fabric unit of each row being engaged by the hooks in which the adjacent sides of adjacent fabric units in an adjacent row terminate, the sides 0 of each fabric unit in each row forming

with the adjacent sides of adjacent fabric units in an adjacent row connected therewith by the hooks of the first fabric unit figures of substantially diamond shape.

In witness whereof, I hereunto subscribe 15 my name this 9th day of April A. D., 1914.

FRANK P. DOOLEY.
